UNITED STATES PATENT OFFICE.

ARTHUR RIVINGTON MANGNALL, OF CHESTER, ENGLAND.

EARTH-BORING APPARATUS.

Application filed April 29, 1924, Serial No. 709,913, and in Great Britain May 3, 1923.

This invention relates to earth boring apparatus of the kind in which a pilot head is forced through the ground and bores by displacement, and has particular reference 5 to the machine or apparatus employed for imparting the necessary movement to the pilot head.

In British specification No. 153,931 there is described a form of apparatus for the 10 above purpose consisting of hydraulic cylinder and ram which is adapted to be used to push the pilot head through the ground, the cylinder being adapted to be elevated in the boring pit when it is required to exert a 15 pulling action as, for example, when withdrawing the pilot head.

The object of the present invention is to devise an improved form of apparatus for the above purpose and the invention consists 20 in an apparatus which is reversible in its action while remaining undisturbed in the boring pit, such an apparatus being particularly suitable for use when producing enlarged bores since it enables a small bore 25 to be first formed by pushing in the usual manner after which an enlarged boring member may be entered in the bore at the end remote from the apparatus and may then be pulled through so as to enlarge the 30 bore.

It will be understood, however, that the reversal of the apparatus may be employed for withdrawing the pilot or for drawing a lining of any suitable form or a cable or 35 the like into the bore or for any other desired purpose.

The invention also consists in other details and arrangements hereinafter described or indicated.

40 The accompanying drawings illustrate one mode of carrying out the invention:—

Figure 1 is an elevation, partly in section, of one form of apparatus in accordance with the invention;

45 Figure 2 is a plan;

Figure 3 is an end elevation, and

Figure 4 is a sectional elevation;

Figures 5 and 6 are diagrammatic views showing the apparatus in use, and

50 Figure 7 is a view illustrating a detail.

In carrying my invention into effect in one convenient manner, I form my improved apparatus with two side tubes or like members α which by the aid of jack-

ing screws α' or the like may be positioned 55 against end plates or other fittings within the boring pit in order to maintain the apparatus in any position in which it may have been set for the purpose of obtaining the necessary alignment or direction of bore. 60

Mounted upon such side tubes are two cylinders b connected by suitable cross members c having movable or removable clamping devices α by which the parts (such as the pilot bar e , push pipes and the like) to 65 be forced through the bore are securely fixed in the apparatus and either or both of such cylinders may act as hydraulic cylinders, the ram or rams for the same being formed by pistons or enlargements f 70 on the side tubes or like members. The arrangement is such that by suitably controlling the pressure and exhaust by means of a valve or valves g , h provided for the purpose the cylinders and parts carried thereby are movable as a whole in either direction upon the side tubes or like supporting members and the extent of travel of such hydraulic apparatus on the side supports 75 may be adjusted according to the length of 80 push pipes or other apparatus employed.

It will thus be seen that the push pipes or the like may be mounted in position by means of the clamps without disturbance of the apparatus within the boring pit and also 85 the apparatus is readily reversible in its action without it being necessary in any way to alter the setting, adjustment or position of the apparatus within the pit.

In Figure 5 the apparatus is shown as 90 being used for pushing the pilot in the usual manner, while Figure 6 shows the enlarging head i being drawn through to enlarge the bore, while at the same time a pipe or lining k is also being drawn into the bore. 95 Figure 7 shows the enlarging head secured in place by an adaptor l .

Means are provided for laterally and vertically adjusting the apparatus to secure proper alignment.

100 In the construction illustrated there are provided end plates n adapted to abut against the ends of the boring pit and the apparatus is carried by end frames or members n' movable laterally and vertically in relation to the end plates. The lateral movement is effected by the screws p and the vertical adjustment by the screws o ,

the screws σ being movable in slots in the flanges n^2 and the pins σ' being movable in slots in the flanges n^3 in order to permit of the lateral adjustment of the frame members.

Being reversible in its action, the apparatus affords a very convenient means of enlarging a bore in the manner hereinbefore referred to and it may be also employed 10 for simultaneously or subsequently drawing any desired form of liner, cable or the like into the bore.

It will be understood that the invention is not to be limited to the constructional 15 details which are hereinbefore given by way of example, as the essential feature of the invention is the securing of a form of apparatus which is reversible in its action without requiring to be altered in position 20 in the pit and any means by which this object may be achieved must be regarded as falling within the spirit and scope of the invention.

Having now described my invention, what 25 I claim as new and desire to secure by Letters Patent is:-

1. Earth boring apparatus comprising a 30 boring bar, hydraulic means for pushing said boring bar through the earth to form a bore by displacement and means for reversing the operation of said hydraulic means while maintaining substantially the same position as that which it occupied during pushing.

2. Earth boring apparatus comprising a 35 boring bar, hydraulic means for pushing said boring bar through the earth to form a bore by displacement, means for removably securing said boring bar to said hydraulic means and means for reversing the operation 40 of said hydraulic means while main-

taining substantially the same position as that which it occupied during pushing.

3. Earth boring apparatus comprising adjustable side supports, hydraulic means 45 carried thereby for actuating a boring bar, means for reversing the operation of said hydraulic means while remaining undisturbed in the boring pit and means for adjusting the position of said side supports 50 and the parts carried thereby.

4. Earth boring apparatus comprising side supports, hydraulic means carried thereon for actuating a boring bar, means for reversing the operation of said hydraulic 55 means while remaining undisturbed in the boring pit, end plates against which said side supports abut by means of frame members carrying the side supports and means for adjusting said frame members laterally and 60 vertically.

5. Earth boring apparatus comprising side supports, a hydraulic cylinder movably mounted on one of said supports and co-operating with a piston fixed thereon, means 65 for removably securing a boring bar to said movable cylinder and means for supplying fluid pressure to one side or the other of said fixed piston.

6. Earth boring apparatus comprising 70 side supports, a hydraulic cylinder movably mounted on one of said supports and co-operating with a piston fixed thereon, means for removably securing a boring bar to said cylinder, means for supplying fluid pressure 75 to one side or the other of said fixed piston and means for adjusting said side supports laterally and vertically.

In testimony whereof I have signed my name to this specification.

ARTHUR RIVINGTON MANGNALL.
